Primary Examiner — Randall Gholson(74) *Attorney, Agent, or Firm* — Arent Fox LLP(57) **CLAIM**

The ornamental design for a protector case, as shown and described.

DESCRIPTION

FIG. 1 is a front perspective view of a protector case showing my new design.

FIG. 2 is a back perspective view of the design shown in FIG. 1.

FIG. 3 is a front view of the design of FIG. 1.

FIG. 4 is a right side view of the design of FIG. 1.

FIG. 5 is a left side view of the design of FIG. 1.

FIG. 6 is a back view of the design of FIG. 1.

FIG. 7 is a top view of the design of FIG. 1; and,

FIG. 8 is a bottom view of the design of FIG. 1.

1 Claim, 6 Drawing Sheets(56)
